HIS ATTORNEY.

UNITED STATES PATENT OFFICE.

EMILE J. PITRAT, OF URBANA, ILLINOIS.

TELEPHONE-TRANSMITTER.

No. 894,460.

Specification of Letters Patent.

Patented July 28, 1908.

Application filed June 21, 1907. Serial No. 380,087.

To all whom it may concern:

Be it known that I, EMILE J. PITRAT, a citizen of the United States of America, residing at Urbana, in the county of Champaign and State of Illinois, have invented a new and useful Telephone-Transmitter, of which the following is a specification, reference being had to the accompanying drawings illustrating same.

10 My invention relates to transmitters of the granule type, for transmitting speech by means of electricity.

The principal objects of my invention are to provide a transmitter in which the "button" is always in a vertical position regardless of the position of the body or the mouth-piece of the transmitter; to provide a transmitter in which the vibrations of the speaking diaphragm are amplified before they act 20 on the comminuted material, whereby the variation of the resistance of the said comminuted material for a given vibration of the speaking diaphragm is greatly increased, and to provide an improved construction 25 and arrangement of parts in such a transmitter.

Other objects will be apparent from the following specification.

In many telephone transmitters heretofore used the button is mounted directly back of the speaking diaphragm and parallel therewith. With this construction, when the mouth piece is tilted up or down, the button is also tilted from the vertical, which 35 tilting causes the comminuted material in the button to cover more or less of the electrodes, depending upon how much the button is tilted, and thereby vary the talking qualities of the transmitter, sometimes 40 enough to render the transmitter practically useless for conversation.

In the transmitter of my present invention I mount the button at right-angles to the speaking diaphragm and then mount 45 the transmitter as a whole on its support so that the button is held in a vertical position. With this construction and arrangement, when the mouth-piece of the transmitter is raised or lowered the button remains in its 50 vertical position, which insures that the comminuted material in the button always covers the same amount of surface of the electrodes. As the same amount of surface 55 of the electrodes is always covered by the comminuted material, the talking qualities of the transmitter remain the same. With

this transmitter the current required to properly supply the transmitter always remains the same; while in a transmitter where the button is tilted out of the vertical, 60 the current required to properly supply the transmitter varies considerably, depending upon the amount the button is tilted and the amount of surface of the electrodes covered by the comminuted material. 65

In the transmitter of my invention I provide a pivoted lever arm between the speaking diaphragm and the button, the shorter arm being acted on by the vibrations of the speaking diaphragm and the longer arm 70 acting on the comminuted material in the button, whereby the vibrations of the speaking diaphragm which are transmitted to the button are greatly amplified.

By reference to the accompanying drawings, Figure 1 is a side elevation of the preferred construction of the transmitter of my invention, with portions removed; Fig. 2 is a back elevation of the transmitter shown in Fig. 1, with the ordinary inclosing shell 80 removed; and Fig. 3 is a detail view of the button, the speaking diaphragm and the pivoted lever connecting the button with the speaking diaphragm, the button being shown in elevation and the speaking dia- 85 phragm being shown on edge as if the position of the mouth-piece of the transmitter were directly downward from the position shown in Figs. 1 and 2.

Like characters refer to like parts in the 90 several figures.

The transmitter illustrated comprises the usual front plate 1, mouth-piece 2, speaking diaphragm 3, annular rubber fold 4 for the speaking diaphragm, dampener springs 5 and 95 6, and the usual inclosing shell (not shown in the drawings). The transmitter bridge comprises a metal plate 7 carrying a block of insulating material 8, preferably of hard rubber, the plate 7 being secured to the front 100 plate 1 of the transmitter by screws 9 and the block 8 being cut away at 10 as shown in Fig. 2 and having a projecting portion 11 thereon as shown in Fig. 1. The button 12 comprises any suitable form of button having 105 a pair of electrodes with comminuted material therebetween, at least one of the electrodes being adapted to be vibrated. From the rear of the button 12 extends a pin 13 electrically connected with the back electrode of the button and extending through the portion 11 where it is held in place by the 110

set screw 14. The pin 13 is electrically connected with a terminal screw 24 by a metallic ribbon 15. The front electrode of the button is connected with a terminal screw 16 by a suitable conductor 17 which may be a wire or a ribbon as desired. The conductors leading to the transmitter are connected to terminal screws 24 and 16, respectively. A lever having arms 18 and 19 at right angles to each other is pivoted at 20-20 on brackets 23-23 which are mounted on the insulating block 8 preferably as shown, the long arm 19 of the lever being connected to the front electrode of the button by a nut 21 and the short arm 18 being connected to the speaking diaphragm 3 by a rod 22 preferably as shown in Fig. 3. The vibrations of the speaking diaphragm 3 are transmitted through rod 22 to the short arm 18 of the lever, and thence through the lever to the long arm 19 thereof which communicates the vibrations to the front electrode of the button. It will be seen that as the long arm 19 is on the button side of the pivot 20 and the short arm 18 on the diaphragm side of the pivot 20, the vibrations of the speaking diaphragm 3 are amplified before acting on the front electrode of the button. It will therefore be seen that the vibrations on the comminuted material, and the consequent variations of resistance thereof, are much greater than if the speaking diaphragm 3 acted on the front electrode of the button directly. This construction gives a very sensitive and powerful transmitter. The transmitter may be adjusted by adjusting the button by means of the pin 13 and the set screw 14.

It will be seen that when the transmitter is in the position shown in Figs. 1 and 2, the button stands in a vertical position, and remains in a vertical position even if the mouth-piece 2 and the body 1 of the transmitter are turned down far enough to place the speaking diaphragm 3 in the position shown in Fig. 3. The mouth-piece 2 and the frame 1 of the transmitter may be turned clear around in a vertical plane without in the least tilting the button 12 out of its vertical position. Thus it will be seen, as hereinbefore stated, that the talking qualities of the transmitter and the proper amount of current for operating the transmitter, remain constant at all times.

I do not wish to limit this invention to the particular details of construction as herein shown, as many modifications may be made therein without departing from the scope of the appended claims.

What I claim as new and desire to secure by Letters Patent, is:

1. In a transmitter of the character described, a speaking diaphragm, and a button containing comminuted material, vibratively connected with the said diaphragm

and arranged in a vertical position at right angles to the diaphragm whereby the latter may be tilted without affecting the vertical position of the button.

2. In a transmitter of the character described, a speaking diaphragm, a button arranged vertically and located at right angles to the diaphragm whereby the latter may be tilted without affecting the vertical position of the button, and an elbow lever arm vibratively connected between the speaking diaphragm and the button whereby the vibrations of the speaking diaphragm are amplified to produce an increased vibration at the button.

3. In a transmitter of the character described, a speaking diaphragm, a button containing comminuted material arranged vertically and mounted at right angles to the diaphragm whereby the latter may be tilted without affecting the vertical position of the button, a rod extending through the center of the diaphragm and rigidly secured thereto, and an elbow lever having a short arm connected with the said rod and a long arm connected with the said button, and pivoted between the said arms, whereby the vibrations of the speaking diaphragm are amplified upon being communicated to the button.

4. In a transmitter of the character described, a speaking diaphragm located substantially vertically, a button containing comminuted resistance material and located vertically in a plane at right angles to the speaking diaphragm, and a lever vibratively connecting the speaking diaphragm with the said button, whereby the speaking diaphragm may be tilted from its vertical position without affecting the vertical position of the said button.

5. In a transmitter of the character described, a speaking diaphragm held in a substantially vertical position, a button containing comminuted resistance material and mounted at right angles to the speaking diaphragm in a substantially vertical plane, a rod extending through the center of the speaking diaphragm and rigidly secured thereto, and an elbow lever having a short arm connected with the said rod and a long arm connected with the said button, whereby the vibrations of the speaking diaphragm are amplified before being utilized at the said button, and whereby the speaking diaphragm may be tilted out of its vertical position without affecting the vertical position of the said button.

6. A transmitter of the character described, comprising a front plate carrying a mouth-piece, a bridge comprising a block of insulating material suitably mounted upon the back of the front plate, a speaking diaphragm carried by the said front plate, a suitable button containing comminuted material, carried by the said block of insulating

material substantially at right angles to the speaking diaphragm in a substantially vertical position, a rod extending through the center of the speaking diaphragm and rigidly secured thereto, brackets carried by the said block of insulating material, and an elbow lever having a short arm connected with the said rod and a long arm connected with the said button, and pivoted between the said arms on the said brackets, whereby the vibrations of the speaking diaphragm are amplified upon being communicated to the said

button, and whereby the speaking diaphragm may be tilted without affecting the vertical position of the said button.

As inventor of the foregoing, I hereunto subscribe my name in the presence of two subscribing witnesses this 14 day of June 1907.

EMILE J. PITRAT.
